UNITED STATES PATENT OFFICE.

EDMUND R. ANGELL, OF DERRY, NEW HAMPSHIRE.

ACETYLENE-GENERATOR.

1,089,355.

Specification of Letters Patent.

Patented Mar. 3, 1914.

Application filed March 21, 1911. Serial No. 616,025.

To all whom it may concern:

Be it known that I, EDMUND R. ANGELL, a citizen of the United States, residing at Derry, in the county of Rockingham and 5 State of New Hampshire, have invented a new and Improved Acetylene-Generator, of which the following is a specification.

It belongs to that class of acetylene generators known as carbid-feed, in which calcium carbid, in small quantities at a time, is 10 automatically dropped into water.

The object of my invention is to produce an acetylene generator for service out of doors in winter as well as in summer.

15 In this application I do not claim the mechanism for feeding carbid, as this is shown and claimed in my copending application Serial No. 387215 filed Aug. 5, 1907.

I accomplish this in the following manner:

Figure 1 is an elevation of my device. Fig. 2 is a vertical section of it. Fig. 3 is a sectional view taken on the line 3 3. And Fig. 4 is a sectional view in the plane 4 4.

25 Like reference letters represent corresponding parts in the several figures.

A and B represent two concentrically located hollow cylinders, and C, the gasholder floating in suitable liquid in the annular 30 space between them. The annular disk D, fastens the two cylinders together and forms the bottom of the annular space between them, which is the gasholder seal.

E is the carbid chamber, or hopper. It is 35 formed by the upper part of the cylindrical shell B, and a frusto-conical bottom. Its small end is the mouth of the carbid chamber, or hopper, through which carbid drops. It is closed by a conical valve F, which is 40 attached loosely, by a ball and socket joint, to the rod G, which is suspended from the lever H by the pivot I. The lever is pivoted at J to the support K. The over-counterpoising weight L, is pivotally suspended 45 from the short arm of the lever, and its lower end slides vertically in the guide N. The cover R, together with the support K, and a casing, prevents carbid falling into the gas chamber M.

50 S is a guard sleeve rigidly fastened to the support K, surrounding a portion of the rod G to keep the carbid from impeding its motion.

T is a disk lying upon the top of the 55 sleeve S. The rod G slides through it

loosely. It prevents carbid entering the sleeve.

U is a friction wheel adapted to roll on the lower surface of the disk V, which is attached transversely to the end of the screw 60 W. This screw works in the nut X, which is fixed in the top of the gasholder.

Y is the handle for turning the screw, and Z is packing between its handle and the nut.

O is a nipple, fixed in the top of the gas- 65 holder, through which carbid is introduced into the hopper.

P is the cap, which closes it, and Q is packing between the cap and the nipple.

A' is one of the guide rods for the gas- 70 holder, and is fastened at B' to the top of the cylinder A.

C' is a guide arm on the gasholder engaging the rod.

D' is a chain, whose links are adapted to 75 engage the hook E' fastened to the top of the gasholder. By this means the gasholder may be held suspended whenever desirable.

F' is a guard thimble to prevent moisture running down the lower surface of the hop- 80 per upon the valve F.

G' is a base, or bed-ring, an iron ring 85 rabbeted on its upper inner edge, and on its lower surface. The inner wall of the gas- holder seal, which is the cylinder B, ex- tends below the bottom D of the seal and is fastened to the inner surface of the iron ring G' so that the cylinder B and the rab- 90 bet on the upper face of G' form a gutter H' which is rectangular in cross section en- circling the machine. The bottom, D, of the seal is above the gutter by a small space, so that the whole top of the gutter is open. This construction allows free access for 95 water to the gutter, to flow around it and escape by the outlet J'.

I' is a dam across this gutter and J' is the outlet from it.

K' is a packing ring in the groove of the lower rabbeted surface of the iron ring G'. 100

M' is the detachable generator pail and its top edge is adapted to secure a tight joint with the packing ring K'.

L' L' are lugs fastened to the pail M' on 105 diametrically opposite sides, and near its top.

N' N' N' are legs to support the machine. They are fastened, at points of one hundred and twenty degrees apart, to the iron ring G' and to the hoop O', by means of cap 110 screws.

Q' is a bail-shape lever. It is pivoted at each end to one of the legs N' at P' P', Fig. 3. Equally distant from the pivoted ends of this lever and on diametrically opposite sides of the machine, two depending hooks R' R' facing in opposite directions, are fastened to the lever, adapted to engage the lugs L' L' on the pail M'. An eccentric S', provided with a handle, is pivoted to the lever at its center and opposite the third leg N', adapted to work against the shelf T', which is attached to the iron ring G' and extends outwardly beyond the leg.

H'' is an adjustment screw working 15 through the shelf T', and against the eccentric S'. Its service in conjunction with the eccentric, is to adjust the tension of the lever Q'. By the operation of the eccentric, the bail-shape lever is forced up or let down, so 20 that the top of the pail M' is caused to press tightly against the packing ring K', or released therefrom. When the pail is released from the packing ring, it can be completely removed by giving it a slight rotary motion 25 to disengage the lugs L' L' from the hooks R' R', since they face in opposite directions. The pail is secured in place by reversing the operation.

U' is a frusto-conical pipe fastened to the 30 frusto-conical bottom of the carbid chamber, and around its mouth. It extends downwardly nearly to the iron ring G', and is there tightly connected with the cylinder B by means of the annular ring V'. The 35 space within the cylinder B, frusto-conical pipe U', annular ring V', and bottom of the carbid chamber, constitutes the gas chamber M.

Y' is the gas exit, or service pipe, leading 40 from the gas chamber.

W' is a filter pocket placed within the chamber M and over the inner end of the service pipe.

X' is the entrance to the pocket, through 45 which filtering material is introduced and removed.

The operation of the device is as follows: The generator is installed by placing it upon a level foundation and connecting it with 50 the piping of the house. Then the gasholder seal is filled with suitable liquid. One of the detachable generator pails (they are furnished in duplicate) is nearly filled with water and secured in place in the manner 55 already described. When both the gasholder and screw W are in their lowest position, the disk V holds down the long arm of the lever, so the mouth of the hopper is open. But, if now the screw W is turned up 60 to its highest position, the disk V will be raised from contact with the lever H, and the over-counterpoising weight L will seat the stopper F, closing the feed. While the feed is thus closed, the charge of calcium carbid is introduced into the carbid chamber 65

through the nipple O, and the cap P screwed on. The screw W with its transverse disk, together with the lever H pivoted at J, the over-counterpoising weight L, and stopper F pivotally suspended from H by the rod G, provides means both for closing the feed from the outside, so that calcium carbid can be introduced into the carbid chamber without falling through it, and for causing the initial action of the feed 70 from the outside. Without the screw W with its transverse disk controlling the feed as described, the device would be inoperative and worthless. When the screw is turned down, after carbid is introduced into the chamber, some of it is caused to fall into the water contained in the detachable generator pail, the resulting gas raises the gasholder and the machine is then in operation. The gas, from the detachable generator pail, 75 passes up through the pipe U' into the carbid chamber through the space between its mouth, and the stopper F. In passing through the carbid in the hopper it is dried before it reaches the gasholder. From the gasholder it enters the gas chamber M through the opening around the weight L. Thence it passes through the filter W' into the service pipe. 80

The use of the gas chamber is to counteract the effect of air which enters the generator when the detachable pails are exchanged. It does this both by blocking out some of the space which air could readily enter, and by overbalancing, by its volume 90 of gas, the small quantity of air which does enter. Should it be desirable at any time to detach the generator pail for any purpose, or to remove the cap P when the gasholder is up, either to introduce more carbid, or ascertain whether much remains in the carbid chamber, the chain link near the hook E' is first attached thereto to keep the holder suspended, and then the cap is removed. In freezing weather, the detachable 95 generator freezes to the gasket. It is thawed therefrom by pouring hot water into the gutter H' to flow around it. Then the pail can be detached and the residuum easily removed after pouring warm water upon the 100 outside of the pail. 110

Having thus fully described my invention, I claim as new and desire to secure by Letters Patent the following:

1. In an acetylene generator, a solid iron 115 base ring rabbeted on the inner edge of the upper face to form a rectangular gutter with the extended inner wall of the gasholder seal, and said ring also rabbeted on the lower face to receive a gasket, in combination with a detachable generator pail adapted to secure a tight joint with said gasket, and the hereinbefore described mechanism for holding said pail tightly against said gasket. 120

2. In an acetylene generator, mechanism for holding a detachable generator pail tightly against the body of the apparatus, consisting of a solid bed-ring provided with a gasket, legs firmly attached to said bed-ring supporting the entire machine, a bail-shape lever, pivoted at either end to a leg extension and just above the bed-ring, two depending hooks fastened to said bail-shape lever on diametrically opposite sides of the generator and facing in opposite directions, adapted to engage lugs on said detachable generator pail, a shelf fastened to said bed-ring and extending outwardly, an eccentric provided with a handle and pivoted to the center of said bail-shape lever, adapted to press upon said shelf and thereby raise or lower said lever to force the top of said detachable generator pail tightly against said gasket, or release it therefrom as said eccentric is turned by its handle, in combination with a floating gasholder, and mechanism for feeding carbide into water contained in said detachable generator pail.
- 25 3. In an acetylene generator, a floating gasholder, a carbide chamber, carbide feeding mechanism, a gas chamber to block out air space and to diminish, by its large volume, the small quantity of air, which gets within the apparatus during the exchange of detachable generator pails, said gas chamber consisting of the space between the inner wall of the gasholder seal and a frusto-conical pipe through which carbide falls into said 35 detachable pail, its roof, the frusto-conical bottom of said carbide chamber, and its floor,

the annular ring fastening said frusto-conical pipe and the inner wall of the gasholder seal together, in combination with a detachable generating chamber, and the hereinbefore described means of attaching said chamber to the body of said acetylene generator.

4. In an acetylene generator, a detachable generating chamber, its top edge adapted to secure a tight joint against a packing ring 40 on the body of the machine, two lugs fastened to said chamber on diametrically opposite sides near its top, mechanism for holding said detachable generating chamber 45 tightly against the body of the apparatus and releasing it therefrom, consisting of a solid bed-ring provided with a gasket, a bail-shape lever pivoted at each end, an eccentric pivoted to the center of said lever and provided with a handle for turning it, a 50 shelf on said bed-ring to support said eccentric, two depending hooks attached to said lever equally distant from its pivots and adapted to engage said lugs on said generating chamber, whereby said chamber 55 is forced tightly against said gasket, or released therefrom, according to the way said eccentric is turned by its handle, means for feeding carbide into water, a floating gasholder, and means for holding said gasholder suspended during the exchange of said generating chamber for another in recharging.
